PATENTED DEC. 12, 1905.

E. HORAZDOVSKY.
GRAIN SEPARATOR.
APPLICATION FILED JULY 25, 1905.

2 SHEETS—SHEET 2.

UNITED STATES PATENT OFFICE.

EDWARD HORAZDOVSKY, OF MONTGOMERY, MINNESOTA.

GRAIN-SEPARATOR.

No. 807,079.

Specification of Letters Patent.

Patented Dec. 12, 1905.

Application filed July 25, 1905. Serial No. 271,206.

To all whom it may concern:

Be it known that I, EDWARD HORAZDOVSKY, a citizen of the United States, residing at Montgomery, in the county of Lesueur and 5 State of Minnesota, have invented a new and useful Grain-Separator, of which the following is a specification.

This invention relates to grain separators and cleaners; and it has for its objects to simplify and improve the construction and operation of this class of devices.

With these and other ends in view, which will readily appear as the nature of the invention is better understood, the same consists in the improved construction and novel arrangement and combination of parts, which will be hereinafter fully described and particularly pointed out in the claims.

In the accompanying drawings has been 20 illustrated a simple and preferred form of the invention, it being, however, understood that no limitation is necessarily made to the precise structural details therein exhibited, but that changes, alterations, and modifications 25 within the scope of the invention may be made when desired.

In said drawings, Figure 1 is a side elevation, partly in section, of a grain-separator or fanning-mill constructed in accordance 30 with the principles of the invention. Fig. 2 is a longitudinal vertical sectional view. Fig. 3 is a vertical sectional detail view. Fig. 4 is a perspective detail view of one of the screen-frames inverted. Fig. 5 is a sectional 35 detail view taken on the plane indicated by the line 5-5 in Fig. 1.

Corresponding parts in the several figures are indicated throughout by similar characters of reference.

40 The frame of the improved separator or fanning-mill, which is of ordinary construction, is designated F, and it includes a casing C for a fan G, which latter is mounted upon a transverse shaft 1, bearings for which are provided 45 in the sides of the casing. The latter supports a hopper 2, having a feed-opening 3, beneath which is supported a slide 4 operable by a lever 5 to regulate the size of the feed-opening.

50 The shaking-shoe 6 is supported by means of straps 7, the upper ends of which are hingedly connected with the frame so as to permit the shoe to vibrate laterally. The lower ends of the front straps 7 are connected with the frame by means of links 8, whereby 55 longitudinal vibration is prevented, it having been found that longitudinal vibration is non-

essential to the successful operation of the machine, which latter, when the shoe is permitted to vibrate longitudinally, is unnecessarily racked and strained. The shoe is provided in its upper part and in rear of the portion of the fan-casing with a transverse bar 9, having a groove 10 for the reception of the upper portion of a screen-frame 11, containing any desired number of sieves or screens 12. 60 The lower edge of said screen-frame is supported upon the upper edge of an inclined board 13, constituting the bottom of the rear portion of the shoe. Between the sides of the latter, which are spaced apart by a rod 14, are 65 mounted a pair of brackets 15, having ears 16 hingedly engaging the rod 14 upon which said brackets may turn to the position indicated in dotted lines in Fig. 2 of the drawings. This is in order to admit of the 70 convenient insertion and removal of the screen-frame, which latter is retained securely in position by means of the bracket members when they are positioned as shown in full lines in Figs. 1 and 2 of the drawings. Fastening means, such as hooks and staples 17 75 18, may be used to retain the bracket members in the position shown. The said bracket members support an inclined trough or chute 19, discharging at one side of the machine and 80 disposing of the overtail from the screens 12. 85

The screen-frame 11 is provided upon its under edges with cleats 20, having slots 21 in which a deflecting-board 22 is adjustably mounted, said board being parallel with the 90 sieves 12.

The shoe is provided in its lower portion with downwardly and forwardly inclined guides 23, between which is movably supported a screen 24. The upper face of the latter 95 is protected from the impact of the blast from the fan by means of a curved deflecting-shield 25, the lower edge of which is but slightly spaced from the upper surface of the screen, while the upper edge of said shield is sufficiently elevated to prevent it from interfering with material passing through the screens 12. A guide-board 26 extends from a point 100 in the neighborhood of the tail end of the lowermost screen 12 in a downward and forward direction to overlap the screen 24. 105

At the lower edge of the inclined bottom board 13 is supported an inclined chute or conductor 27, which serves to convey material to an elevator 28, whereby it is returned 110 to the hopper 2 of the machine. The elevator, which may be of any well known and

approved construction, is driven from the fan shaft 1 by means of a link belt 29, connecting a sprocket-wheel 30 upon the fan-shaft with a sprocket-wheel 31 upon the lower elevator-shaft. The fan may be driven by a spur-wheel 32, journaled upon the frame of the machine and having a crank 33, said spur-wheel meshing with a pinion 34 upon the fan-shaft. Pivottally connected with 5 said pinion is a pitman 35, the opposite end of which is connected with one arm of a bell-crank lever 36, the other arm of which is connected by a link 37 with the proximate side of the shaking-shoe to which the desired laterally-vibratory movement is thus imparted.

In lieu of the screen-frame 11 (shown in Fig. 2 of the drawings) another frame, as 11^a, containing but two comparatively coarse screens may be substituted, as will be seen in 20 Fig. 3. This screen, which is intended to be utilized when coarse grain, corn, beans, or the like is to be cleansed, is of coarser mesh than the screens 12, and in its use the cleats 20 and the adjustable gage-board 22 may be 25 dispensed with.

The operation and advantages of this improved grain-separator will be readily understood from the foregoing description, taken in connection with the drawings hereto annexed. The gage-board 22 may be adjusted at various distances from the discharge ends 30 of the screens 12, according to the condition of the grain that is to be operated upon. The air which is set in motion by the fan G will 35 pass upwardly and rearwardly through the screens 12, carrying off the chaff, dust, and light impurities. The tailings passing over the screens 12 will be caught in the trough 19. The pure grain which passes through 40 the upper portions of the screens 12 will drop onto the screen 24, where it is freed from cockle and other small seeds, the highest grade of grain tailing over the screen 24. Grain which is not perfectly separated will be 45 intercepted by the gage-board 22 and will

pass through the lower end of the bottom screen 12, onto the inclined bottom board 13, and thence over the conveyer 27 to the elevator, whereby it is returned to the hopper. The guide-board 26 intercepts the high-grade grain passing through the screens 12 and conducts the same to the screen 24, thus preventing any portion of the high-grade grain from being returned to the hopper.

Having thus described the invention, what 55 is claimed is—

1. A shaking-shoe having a grooved cross-bar and provided with hinged brackets supporting a tailings-trough, in combination with a screen-frame supported at its upper 60 edge in said cross-bar and engaged at its lower edge by said brackets.

2. A shaking-shoe having a grooved cross-bar near its upper front portion and an inclined bottom board at its rear portion, and 65 brackets hingedly connected with said shoe and a tailings-trough supported by said brackets, in combination with a screen-frame supported at its upper edge in the grooved cross-bar and at its lower edge upon 70 the upper edge of the bottom board; the lower edge of said screen-frame being operatively engaged by the hinged brackets.

3. In a grain-separator, a shaking-shoe, a screen-frame supported therein, a gage-plate 75 connected adjustably with said screen-frame, an inclined bottom board in the shoe, a guide-board between the bottom board and the gage-plate, a cockle-screen disposed to receive material guided thereto by said board, 80 and a curved shield above said cockle-screen to protect the latter from the impact of blast from the fan which is a part of the machine.

In testimony that I claim the foregoing as my own I have hereto affixed my signature 85 in the presence of two witnesses.

EDDIE HORAZDOVSKY.
